UNITED STATES PATENT OFFICE

1,982,652

ADJUSTABLE FRUIT BOX LID

Harry W. Foley, Fresno, Calif.

Application February 13, 1933, Serial No. 656,545

5 Claims. (Cl. 217—56)

This invention relates to lids for boxes in which fruit is shipped; my principal object being to provide a unitary lid which may be adjusted when being mounted on the box as to its height from the top of the box without reversing the lid, while maintaining the same overall length of the lid in either position. By this arrangement the cover may be disposed on the box in proper relation to the depth of the pack, or so as to increase the ventilation if desired; and the same side of the lid is always up so that the label of the shipper or other identifying or other advertising matter on said one side of the lid will serve with both positions of the lid.

15 A further object is to arrange the device so that the ends of the lid proper are always disposed between the box ends and the relatively heavy end cleats of the lid so that protection against the lid being accidentally ripped off is afforded. Also, no tools or implements of any kind are necessary in adjusting the lid from one position or the other and the boxes themselves are not disturbed or altered in any way.

member scored transversely adjacent its ends to permit downward bending of the lid, and cleats secured on the lid immediately beyond the scores; the lid beyond the cleats being bent to form flanges abutting against and secured to the opposed faces of the cleats.

3. A lid as in claim 2, in which the cleats are square in cross section.

4. A box cover comprising a relatively flexible lid, cleats secured to the lid adjacent its ends and adapted to be turned on their longitudinal axes

to selectively raise and lower the lid relative to the box, the lid being scored adjacent the cleats to facilitate such movement.

5. A box cover comprising a lid, cleats secured to the top surface of the lid adjacent the ends thereof, the lid being bendable immediately along the inner edges of the cleats whereby the latter may be turned about their longitudinal axes to selectively raise or lower the lid relative to the box.
